DESIGN FOR A HINGE

Charles L. Heizmann, Cumru Township, Berks County, Pa., assignor to Earle Hardware Manufacturing Co., Reading, Pa., a corporation of Pennsylvania

Application March 25, 1938, Serial No. 76,100

Term of patent 14 years

To all whom it may concern:

Be it known that I, Charles L. Heizmann, a citizen of the United States, residing at Cumru Township, in the county of Berks and State of Pennsylvania, have invented a new, original, and ornamental Design for a Hinge, of which the following is a specification, reference being had to the accompanying drawing, forming part thereof.

Fig. 1 is a front perspective view of a hinge in open position showing my new design.

Fig. 2 is a top plan view of the same.

Fig. 3 is a side view.

I claim:

The ornamental design for a hinge, as shown.

CHARLES L. HEIZMANN.
